UNITED STATES PATENT OFFICE.

ROBERT G. VASSAR, OF NEW YORK, N. Y., ASSIGNOR OF TWO-THIRDS TO GARRETT S. MOTT, OF PHILADELPHIA, PA., AND JAMES G. SMITH, OF HACKENSACK, N. J.

ALARM-LOCK.

SPECIFICATION forming part of Letters Patent No. 293,690, dated February 19, 1884.

Application filed September 18, 1882. (Model.)

To all whom it may concern:

Be it known that I, ROBERT G. VASSAR, a citizen of the United States, and a resident of New York, in the county of New York and State of New York, have invented a certain new and useful Alarm-Bolt, of which the following is a specification.

The object of my invention is to so combine a bolt with an alarm mechanism that the latter will be caused to give a signal upon the attempt of an intruder to open the door to which the bolt is applied, or upon an attempt to manipulate or gain access to the bolt by any unauthorized means.

15 My invention consists in so arranging the bolt and alarm that the alarm mechanism will be released upon either a longitudinal movement of the bolt from the outside of the door, or a lateral movement of the same due to the 20 pressure upon it of a tool, or to an attempt to open the door before the bolt is thrown back.

25 My invention also consists in so combining the parts that the operation of the bolt from the inside of the door by the key or knob provided for the purpose will carry the releasing portion of the bolt out of range of the detent by which the alarm is released, so that the longitudinal movement of the bolt will not in this case cause the alarm to sound.

30 My invention consists, further, in a certain novel construction and arrangement of the operating-knob, whereby it is normally held out of connection with the bolt in such a way that the bolt cannot be readily operated by a 35 tool inserted into the bolt-casing.

My invention further consists in the combination, with the catch or stop for a detent-arm, applied to the mainspring-shaft of the alarm mechanism, of a novel guard-plate, which 40 allows said shaft to make its full number of revolutions in running down or in winding up without interference from the stop.

45 My invention also consists in certain novel combinations of devices that will be specified in the claims.

In the accompanying drawings, Figure 1 is a side view of the containing-case for the bolt and alarm mechanism, showing the setting-

handle for the latter and the operating knob or handle for the bolt. Fig. 2 shows in side elevation the operative portions of the device, the casing being in section. Fig. 3 is a vertical section on the irregular line *xx* of Fig. 2. Fig. 4 is a vertical section on the straight line *yy* of Fig. 2. Fig. 5 shows in detail the parts 55 of the guard-plate applied to the stop for the detent-arm of the alarm mechanism.

A indicates the containing-casing, and C the bolt, which slides on the face of a vertical guide-plate, V, secured to the interior of the casing, being held against said plate by a spring, P, affixed to a stud, Z, which latter serves to limit the lateral movement of the free end of the bolt when it is forced to one side either by a tool or an attempt to enter 65 the door when bolted. The end of the bolt C projects through the edge of the casing, the opening being sufficiently large to allow the opposite end of the bolt to move laterally or longitudinally while supported at the edges 70 of the opening, as upon a fulcrum. A spring, Q, serves to normally hold the free end of the bolt down, except when it is raised by the operation of a key or knob, to be presently described, while a coiled spring, W, tends to 75 normally hold the bolt back. A pin, Y, holds the bolt "shot;" but when the free end of the bolt is raised, so as to disengage it from the pin, the spring W throws the bolt back.

K indicates a detent-arm secured to the arbor of the mainspring J for the alarm mechanism, and adapted to engage with a stop formed by a shoulder or step upon the edge of a horizontal plate, L, supported by the plate V, or in any other suitable manner. When so 80 engaged the alarm mechanism is prevented from acting. The end of the detent-arm projects upward above the lower edge of the bolt, and also into the path of a shoulder or projection, N, upon the side of the bolt, so that, as 85 will be readily seen, the detent will be sprung out of engagement with the stop if the bolt is forced against it laterally either by a tool or by the swinging of the bolt upon its fulcrum when an attempt is made to open the door 90 without throwing the bolt back, or, if the bolt

be moved back longitudinally in the event of pin Y being broken off or removed, so as to cause the beveled or rounded shoulder N to come into engagement with it.

5. The alarm mechanism is of any desired kind, that here shown consisting of the toothed wheel D, secured to the mainspring-arbor, the spring J fastened at one end to a fixed post and at the other end to the arbor, pinion I, 10 gearing with wheel D, escapement-wheel F, vibrating escapement H, bell-hammer G, connected thereto, and bell B.

E is a plate secured upon studs projecting from the side plate of the casing, in which 15 plate one end of the spindles of the alarm mechanism are supported, while the other ends are supported in the side plate of the casing A or in any other suitable manner.

T is a handle fixed to the mainspring-arbor, 20 by means of which the alarm mechanism is wound up and the detent K set in engagement with its stop. The words "up" and "down" upon the casing indicate the condition of the alarm mechanism—that is, whether it is wound 25 up or run down.

In order to allow the arm K to pass the stop or shoulder on the stop-plate L in the act of running down or winding up, I have devised what I term a "guard-plate," (shown in 30 detail in Fig. 5,) and consisting of a plate, M, having an elongated opening or slot, O, through which passes a pin secured to plate L. A spring applied to the guard-plate tends to hold it out, and in the position shown in Fig. 5, so 35 that its edge projects beyond the upper edge of the shoulder upon the stop-plate, and in the act of winding up the arm K will come into engagement with the guard-plate, but will force the same over to one side until it snaps 40 by it. When, however, the arm is disengaged from the step or shoulder on the plate L, so as to release the alarm mechanism, said arm moving in the reverse direction will ride upon the curved edge of the guard-plate, and will 45 thereby be kept from engaging with the step. The mechanism is thus allowed to run completely down. To set the device, the mechanism is wound up and the arm K turned until it comes against the square edge of the 50 plate M, at which point it is stopped and allowed to engage with the shoulder on the plate L.

S is the knob or handle by means of which the bolt is operated from the inside of the 55 door, so that it can spring back without affecting the alarm. The handle S is fixed permanently or otherwise, as desired, to the operating arm or key R, which plays between two stops, X X, and is mounted upon a spindle carrying a coiled spring, as shown, which latter serves to hold the arm out of line with the bolt until said arm is forced back against the tension of the same into position, where its web may, by turning the handle, be caused 65 to lift the bolt away from the stop-pin Y.

As the arm R is turned, it lifts the free end

of the bolt, which then rides on the pin Y, so that the shoulder N passes above the detent K and avoids it when the bolt is forced back. By this means the alarm mechanism 70 is prevented from acting. By a reverse movement of the arm the bolt is thrown back to lock the door, the spring Q at the same time acting to force its free end down, so as to cause it to engage with the pin Y.

I do not limit myself to any particular construction of the alarm mechanism, as it is obvious that many other forms may be used in its place. It is also obvious that other detent devices might be used in place of the 80 spring-arm K, if properly arranged to be operated and released by the sidewise movement of the free end of the bolt, or by the shoulder N, or equivalent device, upon a longitudinal movement without lifting.

What I claim as my invention is—

1. The combination, substantially as described, of an alarm mechanism and detent with a laterally and vertically movable sliding bolt having its fulcrum in the edge of the 90 casing, and provided with a releasing shoulder or projection for releasing the alarm mechanism upon a longitudinal movement of said bolt in a straight line.

2. The combination, with a laterally and vertically movable bolt, of an alarm mechanism whose detent is arranged in the path of the bolt when moved laterally by any unauthorized means, a releasing projection or shoulder upon the side of the bolt for releasing the alarm mechanism upon a longitudinal backward movement in a straight line, and an operating key or knob for throwing back the bolt, constructed in the manner described, to lift the end of the bolt carrying the releasing projection, so that the latter will avoid the 105 detent of the alarm mechanism.

3. The combination, with the alarm-detent mounted on mainspring-arbor of an alarm mechanism, of the bolt C, having operating shoulder N, and the lateral and vertical pressure-springs P Q, as and for the purpose described.

4. The combination, with the alarm-detent, of the bolt C, projecting through an opening 115 in the casing, and adapted to have a vertical and lateral movement upon the edges of said opening as a fulcrum, and alarm-detent arranged in the path of the releasing-projection N upon the bolt, and an operating knob or handle, S, provided with means for lifting the free end of the bolt, so that when the bolt is thrown back the alarm will not be sounded.

5. The combination, with an alarm mechanism, of the bolt C, confined at one end within 125 an opening in the casing and free to move vertically and horizontally at its other, the spring W, the catch Y, and the operating knob or handle for lifting the free end of the bolt.

6. The combination, with the bolt C, arranged in the manner described, to move vertically and horizontally at its inner end, of

the alarm-detent arranged in the path of the operating-projection N, the springs P Q W, applied as shown, stop Z, plate V, and catch Y.

7. The combination of a spring détent-arm 5 mounted on mainspring - arbor of an alarm mechanism, means for holding said detent, and a laterally-movable bolt, as and for the purpose set forth.

8. The combination, with the stop or shoulder for the detent-arm, of a yielding guard-plate 10 normally projecting above said shoulder and adapted to allow said arm to pass the shoulder in either direction.

9. The combination, with the plate L, having a stop or shoulder, and the detent secured 15 to the mainspring-shaft, of the yielding guard-plate M, rounded upon one side, so as to allow the detent to pass the shoulder in running down.

Signed at New York, in the county of New 20 York and State of New York, this 16th day of September, A. D. 1882.

ROBERT G. VASSAR.
